METHOD AND APPARATUS FOR SORTING
STRIP STOCK

William Pechy, Elizabeth, N. J., assignor to
American Can Company, New York, N. Y., a
corporation of New Jersey

Application June 25, 1930, Serial No. 463,710

14 Claims. (Cl. 164—49)

The present invention relates in general to a method and apparatus for sorting strip stock in accordance with surface conditions and has particular reference to the detection and indication of waster spots or other imperfections in the surface of tinplate or other material and the automatic sorting of articles made from the strip.

Tinplate such as is used in the manufacture of tin cans and the like is now being commercially manufactured in strip form, a continuous roll or reel constituting the product as shipped from the tinplate mills. The present invention is primarily directed to an inspecting and sorting method and apparatus, the functions of which are influenced by the surface conditions existing on such strip material. Unlike the inspecting and sorting of sheets, which may be individually retained or rejected according to their surface conditions, the sorting of continuous strip material involves first the discovery of an imperfection and second, the automatic sorting out of the article produced from that portion of the strip containing the imperfection.

The principal object of the present invention is the provision of a method and apparatus for inspecting surface conditions of a strip and sorting cut portions of the strip in accordance with such surface conditions.

An important object of the invention is the provision of a method for subjecting strip stock to a surface detecting operation thence to an imperfection indicating or indexing operation and finally to a sorting operation accomplished in accordance with said indexing.

An important object of the invention is the provision of an apparatus for automatically inspecting surfaces of strip stock and locating the position of such imperfections and further, the provision of automatic mechanism for inspecting surface conditions of a strip, indenting the strip adjacent imperfections in its surface and utilizing the indentations to permit sorting and segregating of imperfect articles cut from the strip.

A further important object of the invention is the provision of a highly sensitive apparatus capable of detecting spots and imperfections of small dimension on the surface of the strip and thereafter impressing indicating marks in the strip for locating the imperfections.

A further important object of the invention is the provision of an apparatus utilizing a continuously operating mechanism for inspecting and indenting a continuously moving strip adjacent

imperfections therein as determined by the inspection.

A still further important object of the invention is the provision of an improved apparatus for cutting articles from a continuous previously inspected strip and separating the articles having perfect surfaces from those which contain surface imperfections.

The invention contemplates the provision of a series of inter-connected electrical circuits operating through suitable surface inspecting, strip indenting, article forming and article sorting devices for automatically sorting articles made from the strip in accordance with surface conditions.

The invention further contemplates the provision of electrical circuits and timing elements operating in connection with suitable devices for automatically sorting articles made from strip stock by first determining the surface condition of the strip and sorting in accordance therewith, the timing elements insuring proper restoration of the electrical circuits in exact synchronism with the various operations after the different circuit operations have taken place.

Numerous other objects of the invention will be apparent as it is better understood from the following description, which, taken in connection with the accompanying drawings, discloses a preferred embodiment thereof.

Referring to the drawings:—

Figure 1 is a schematic showing of an apparatus capable of carrying out the present invention illustrating partly in front elevation and partly in section certain essential mechanisms.

Fig. 2 is a fragmentary plan view of a portion of a strip capable of utilization in the apparatus shown in Fig. 1, certain operations being indicated thereon.

Fig. 3 is a front to back sectional view of the press mechanism illustrated in Fig. 1 and taken substantially along the line 3—3 in that figure.

Fig. 4 is an enlarged sectional detail taken substantially along the line 4—4 in Fig. 1.

Fig. 5 is a fragmentary view similar to Fig. 4 some of the movable elements being shown in a different position.

Fig. 6 is an enlarged longitudinal sectional view taken through a portion of the strip and through the surface inspecting, strip indenting devices and associated parts.

Fig. 7 is an enlarged sectional view taken through the article cutting device, through its associated discharge chutes and through the actuating devices connected therewith.

Fig. 8 is an enlarged sectional view, parts shown in elevation and taken substantially along the line 8—8 in Fig. 1.

Fig. 9 is an enlarged sectional detail taken substantially along the line 9—9 in Fig. 3.

Fig. 10 is a wiring diagram illustrating the electrical circuits utilized in the performance of the various steps of the present invention, certain mechanical elements being indicated without regard to relative positions.

The apparatus shown in the drawings comprises a table over which a continuous strip of sheet material is fed from a reel or roll. This strip passes adjacent light sensitive detecting devices utilizing beams of light which are thrown onto and reflected from the surfaces of the strip. The reflected light beams pass into photo-electric or light sensitive cells which operate, upon a diminution of reflected light occasioned by the passing of a surface imperfection in the strip, to actuate an electrical solenoid.

Action of the solenoid projects outwardly a series of indenting dies carried by a rotating member and indentations are thereby formed along one edge of the strip adjacent the imperfection in its surface. The first of these indentations is somewhat in advance of the imperfection and the indenting operation started by the cell continues for a short time irrespective of the presence or absence of waster spots immediately following. This continuation of operation provides indentations both before and after the imperfection. The indenting action is terminated when the first indentation reaches and engages an electrical switch, the solenoid at that time being deenergized and the indenting dies being then no longer projected.

The indented strip may then be conveyed into another section of the same machine or into another machine either immediately following the indenting operation or at a later time. This second section may embody a press mechanism for cutting articles from the strip and forming them into suitable shape. This is the type of mechanism selected to illustrate the invention but other alternate forms of devices may be used to operate on the indented strip. For example, the end of the strip may be repeatedly cut off as by slitter, shear or other cutting members.

Where a press mechanism is used, the strip is preferably intermittently fed between cutting dies and successive articles are cut one at a time with each operation of the press, any indentations in the edge of the strip being engaged by a device carried upon a suitable press part. When the device is engaged by an indentation, a discharge chute associated with the cutting members is shifted from its normal discharge position into a position where the articles as cut from or adjacent to the imperfect portions of the strip are directed into suitable separate places of deposit. There is thus effected a sorting of the perfect from the imperfect articles as they are removed from the strip.

The mechanism of the apparatus disclosed in the drawings may be divided, for the purposes of the present description, into two general sections and the operations associated with each section will be grouped as far as possible. The first section comprises the feeding of the strip of material along a predetermined path, the inspecting of its surfaces and the indenting thereof adjacent any surface imperfections. The indented strip may then be stored if desired, as previously

suggested, the imperfections being permanently registered or indexed therein.

The strip stock may consist of a continuous web 21 (Fig. 1) wound on a central shaft 22 in the form of a roll or reel 23, which may be suitably supported in uprights 24 resting upon the floor. The strip 21 as fed from the reel passes through directing rollers 25 secured to parallel shafts 26 carried in brackets 27 projected from upright frames 28 resting upon the floor and supporting a horizontal table 29.

The detecting and indenting devices are supported upon the table 29 and the strip 21 is moved over its upper surface by an upper feeding roller 31 and a cooperating lower roller 32. Roller 31 (Figs. 4 and 5) is secured to a horizontal shaft 33 journaled in bearings 34 supported on the table 29.

The lower roller 32 is mounted upon a horizontal shaft 35 journaled in bearings 36 carried by and positioned beneath the table 29. Uniform rotation of the shafts 33 and 35 and their respective rollers 31 and 32 is insured by the use of a spur gear 37 keyed to the shaft 33 and meshing with a similar gear 38 keyed to the shaft 35.

The press parts of the apparatus, these forming the second section previously referred to, may comprise a standard type of supporting legs 39 (Fig. 1) resting upon the floor and connected with side frames 40 tied together by a press bed 41 carrying the usual type of bolster plate 42. The side frames 40 support a crankshaft 43 in bearings 44.

The roller shaft 33 (Figs. 1 and 4) is adapted to receive rotation from the rotating crankshaft 43, the latter for this purpose carrying a sprocket 45 over which operates a chain 46 passing at its lower end over a sprocket 47 mounted on a horizontal shaft 48. This shaft which forms a connecting link between the two machine sections is journaled in a bracket 49 mounted on a feed table 51 carried by the press bed 41 and in a bracket 52 carried by the table 29.

The shaft 48 carries a bevel gear 53 which meshes with a similar gear 54 secured to one end of the shaft 33. By means of the described connection, the feeding rollers 31 and 32 advance the strip 21 over the table 29 in a continuous and uniform rate of travel and in synchronism with the operation of the press mechanism.

The table 29 (Fig. 1) is provided with a central opening 61 in which the detecting device and feeding rollers 31 and 32 are located. The strip 21 after passing through the feeding rollers is guided through idler rollers 62 and 63 mounted on parallel shafts 64 and 65 journaled in bearings 66 and 67 carried by the table 29.

The strip surface detecting device embodies a pair of housings 71 of identical construction, one mounted above and one below the table. Thus positioned one detecting unit is above and one beneath the strip, as it advances through the machine. Each housing 71 encloses a source of light which may utilize an electric light 72 (see also Fig. 6) having its rays of light concentrated in a beam of light indicated by the dotted lines 73, this light passing through suitable lenses 74 which focus the beam and project it at an angle to the strip, one beam striking the upper and the other beam striking the lower surface of the strip.

Each housing 71 encloses a chamber 75 in which is located one or more photo sensitive cells 76 suitably connected in electrical circuits herein-75

after described. The light as reflected from the surface of the strip 21 passes into the cells 16. Any imperfection in the surface of the strip provides a relatively poor reflecting surface and the total amount of light passing into a cell 16 at such a time is sufficiently reduced to influence the flow of the electrical current connected with the cell and control the action of a solenoid connected with indenting instrumentalities. The indenting devices will first be considered.

The roller 31 is provided with a circumferential groove 81 (Figs. 4, 5 and 6) near one end of the roller, so located as to be adjacent one edge of the strip 21 during its passage beneath the roller. The roller 32 is provided with a central bore 82 in which slides a wedge member 83 having a conical wedging surface 84 and having a horizontal stem 85 projecting into a solenoid 86 secured to the table 29. The stem end forms the core of the solenoid. Sliding of the core and the wedge member 83 in one direction takes place whenever the solenoid 86 is energized, this being the solenoid controlled by the photo-electric cells 16. A spring 79 located inside of the solenoid 86 surrounds the stem 85 and acts against a collar 80 on the stem to slide it and the member 83 in the opposite direction when the solenoid is deenergized.

As the wedge member 83 moves from the position illustrated in Fig. 4 into the position illustrated in Fig. 5, its conical surface 84 engages tapered faces 87 of radially disposed indenting pins 88 sliding in radial slots 89 formed in the roller 32. Each pin 88 is provided with a slot 91 in which projects one end of a holding pin 92 carried by the roller 32. This construction permits radial movement of the pin 88 and prevents its displacement from the roller 32.

The pins 88 are thus carried in a circular path of travel by the rotating roller 32 and are positioned directly opposite the annular groove 81 formed in the roller 31. With the pins 88 projected outwardly (Fig. 5) the outer end of each as it comes into engagement with the strip 21, presses a portion of the strip into the groove 81 forming an indentation 93 (Figs. 2 and 6) in the edge of the strip. This indenting operation begins as a waster spot or other imperfection, indicated by the numeral 94 in Fig. 2, passes through the beam of light 73.

When the solenoid 86 is deenergized, the stem 85 is released and moves toward the left under action of the spring 79 (Figs. 4 and 5) and the wedging surface 84 of the member 83, being removed from its expanding position relative to the pins 88, permits the latter, as they engage the strip 21, to move back into the roller 32.

It is advantageous as a feature of safety that the solenoid 86 be energized for a length of time sufficient to impress more than one indentation 93 in the strip 21 and this is provided for in the electrical solenoid circuit hereinafter described.

The indenting operation continues until the first indentation (Fig. 6) reaches an interrupting switch 95 mounted upon the table 29 and embodied in the electrical solenoid circuit. At such time a roller 96, forming a part of the switch mechanism is engaged by the forward indentation and the switch 95 is moved to open position de-energizing the solenoid 86. A description of this action from an electrical standpoint will at present be reserved until the further mechanical features of the apparatus have been described.

As illustrated in Fig. 1, the strip 21 is preferably permitted to sag between the two units of the machine and the loop thus formed permits con-

tinuous strip feeding through the first unit and intermittent strip feeding through the press mechanism.

The advantage of this action is obvious when it is recalled that the cutting action of a press is intermittent. The strip 21 is moved across the feed table 51 and between the cutting members of the press by means of feeding rollers disclosed in detail in Fig. 8. There is accordingly provided an upper roller 101 mounted on a horizontal shaft 102 journaled for rotation in bearings 103 carried by the table 51. A lower feeding roller 104 cooperates with the roller 101 and is secured to a horizontal shaft 105 journaled in bearings 106 carried by the feed table 51. A spur gear 107 keyed to the shaft 102 meshes with a similar gear 108 keyed to the shaft 105 and this insures uniform rotation of the rollers 101 and 104 to advance the strip 21 therebetween and over the table.

The rollers 101 and 104 are intermittently rotated by a pawl and ratchet device. The shaft 102 carries a toothed ratchet wheel 109, the periphery of which is engaged by a pawl 111 pivoted on a pin 112 secured to the end of an arm 113 of a bellcrank lever 114 (see also Fig. 1) mounted upon one end of the shaft 102 and pivotally connected at 115 to a rod 116 in turn connected in a universal joint 117 to the face of a disc 118 carried by the crankshaft 43.

Each rotation of the crankshaft 43 oscillates the bellcrank lever 114 on its shaft 102 and through the pawl and ratchet cooperation the shaft 102 is moved in one direction a given number of degrees. The return oscillation of the bellcrank lever 114 has no effect on the shaft 102 as the pawl 111 at such time moves idly over the ratchet teeth in the usual manner. The roller 101 is provided with an annular groove 121 (Fig. 8) which permits passage of the indentations 93 through the rollers 101 and 104 without ironing out or altering them.

Immediately following each advance movement of the strip 21, the press parts operate and the cutting members thereof remove the articles from the strip. These cutting members may comprise stationary lower die parts (Figs. 1 and 3) of the usual standard type herein designated generally by the numeral 125 and these are mounted upon the bolster plate 42. The movable die parts or punch members designated generally by the numeral 126 are carried on the lower end of a slide 127 connected with a pitman 128 to a crank 129 formed in the crankshaft 43.

As the members 126 move downwardly they cooperate with the members 125 to blank out and form an article from the strip. At the same time a feeler pad 131 (Figs. 1 and 7) moves downwardly toward the strip 21. The pad 131 is carried on the lower end of a sliding stem 132 mounted in a tubular bracket 133 bolted to the slide 127.

The stem 132 is normally projected downwardly from the bracket and in this lowered position an upper enlarged end 134 thereof rests upon a bushing 135 carried in the bracket 133, this position being normally maintained by a spring 136 surrounding the lower end of the stem 132 and confined between the end of the bushing 135 and the pad 131.

The bracket 133 also carries a block 137 which is embedded in an insulating bushing 138. When the pad 131 is in its projected position, the upper end of its stem is spaced from the lower end of the block 137. The pad is carried bodily with

- the slide 127 and if there is a projection 93 directly beneath as the pad moves downwardly, the increased height of the projection above the upper surface of the strip is sufficient to arrest movement of the pad before the slide is fully lowered.
- The pad 131 engaged by the projection is held as the block 137 continues downwardly with the slide whereupon the lower end of the block 137 engages the upper end of the stem 132 and completes an electrical circuit connecting with a solenoid 141 (Figs. 3 and 7) bolted to a side frame of the press. The solenoid 141 is provided with a core member 142 pivotally connected at 143 to an upper chute 145 and at 144 to a lower chute 146. Both chutes 145 and 146 pivot near their lower ends on rods 147 and 148, the rods being suspended between the side frames 40 and held in brackets 150.
- 20 The chute members 145 and 146 are adapted to be moved on their respective pivots 147 and 148 into one of two positions. When the solenoid 141 is energized, this being at the time an indentation 93 is opposite that part of the strip being cut by the cutting members, the two chutes are held in raised position. The lower chute 146 is then in position (Fig. 7) for discharging the cut article, the articles being suitably removed from the cutting members as they separate.
- 25 30 When the solenoid 141 is deenergized, this being at a time when no projection is present adjacent the area of the sheet being cut, the upper chute 145 is in position (Fig. 3) to receive and discharge the cut articles.
- 35 The chute 145 communicates with a suitable place of deposit which may be a box 149 resting upon the floor and adapted to receive the articles having perfect surfaces and in a similar manner a box 151 is provided for articles having 40 surfaces passed by the previously described mechanisms as imperfect and which discharge by way of the chute 146.
- 45 It will be understood that the pad 131 engages a projection 93 in the strip 21 only when the pad is practically at the end of its lowermost travel and the resulting energizing of the solenoid 141 and the shifting of the chute members takes place while the cutting members are separating, this being in sufficient time to catch the article 50 when it is discharged from the cutting members.
- 55 Reference should now be had to Fig. 10, which illustrates diagrammatically the electrical circuits which may be utilized in carrying out the present invention. These different circuits will be arbitrarily named as far as possible in accordance with the operations performed as it is believed such a procedure will assist in distinguishing the circuits one from another. It will be understood that at all times there is a very close 60 connection between many of the circuits and that in some instances, separation of circuits is more or less theoretical.
- 65 Any suitable form of photo sensitive cell may be utilized and the electrical circuit connecting therewith may be of any usual and preferred type. The use of such a circuit being merely incidental to this invention, a detailed description of it will not be undertaken. There are indicated two wires 161 and 162 connecting with the cells 76.
- 70 75 These wires lead into the necessary amplifying unit used in connection with photo electric cells of this nature, the numeral 163 diagrammatically indicating all that is necessary for an understanding of the present invention. This unit may be suitably housed in a casing carried on a

5 bracket 164 (Fig. 1) mounted upon the frame 28.

A contact 166 and a wire 165 delivers the amplified output to a grid 167 of a glow tube 168 of standard construction. This tube will be used as an electric valve and is used because of the relatively slow restoring properties of such a device. A wire 169 leading from the amplifier unit 163 is grounded at 171 and this, together with the wire 165, will provide the path for what will be termed the "glow tube valve circuit." 10

An element 172 of the glow tube 168 is connected with a wire 173 passing to a contact 174 and an element 175 of the tube is connected with a wire 176 passing to a contact 177. The contact 174 is connected to a wire 178 leading into 15 a suitable source of energy which may be a battery 179 while a wire 181 is connected to the opposite side of the battery 179 and a coil 182 of a relay 183, the opposite end of the coil being connected by a wire 184 to the contact 177. 20

As long as the full strength of light is received in the light sensitive cells, the tube 168 is maintained by its "glow tube valve circuit" in condition to prevent flowing of a current through the tube and between its elements 172 and 175. If 25 a surface imperfection, however, passes through the light beam and the volume of light reaching any of the light sensitive cells is reduced, the valve action on the grid 167 breaks down and it no longer performs its current resisting function. 30

Current thereupon flows from the battery 179 along wire 181, through the coil 182, along wires 184 and 176, through the glow tube 168 by passing between the elements 175 and 172 thereof thence by wires 173 and 178 back to the source 35 of energy this constituting what will be termed a "relay circuit". The coil 182 is thereupon energized and the relay 183, which functions as a double switch, moves elements 185 and 186 thereof into connection with respective contacts 187 40 and 188 connected by wires 189 and 191 with a wire 192. The wire 192 is connected at one end with the switch 95 and the opposite side of the switch is connected by a wire 193 to a main lead line 194. 45

The element 185 is involved in another electrical circuit which will be termed a "preparing circuit" since it prepares for the establishment of other circuits. This element is connected by a wire 195 to a coil 196 of a relay switch 197. The 50 opposite side of the coil 196 is connected by a wire 198 to one end of a coil 199 of a second relay switch 201 involved in still other circuits, the opposite end of the coil 199 being connected by a wire 202 to the moving element 186 of the 55 relay 183.

With the contact 187 closed, the "preparing circuit" is established and current flows from the lead line 194 through the wire 193 into the switch 95, which is normally closed at the time the relay 183 is energized. This, it will be recalled, takes place only when a surface imperfection of the sheet is registered by the photo sensitive cell. The current flows through the switch 95, through the wires 192 and 189, through contact 65 187 and relay element 185, through wire 195, coil 196, into wire 198 and thence by a wire 203 and a wire 204 back to a main lead wire 205 on the opposite side from the lead wire 194. 70

Flowing of the current in the "preparing circuit" and through the coil 196 energizes the latter and operates the relay 197 to close a contact 206 which will be utilized in an "indenting circuit" and a contact 207 utilized in a "holding cir- 75

cuit". These contacts are closed by means of a sliding element 208 forming part of the relay.

The relay element 208 is connected by a wire 209 with the wire 192 and upon closing of the contact 207, part of the current flowing through the wire 192 in the "preparing circuit" is diverted into the wire 209, through the element 208, contact 207, coil 196, wires 198, 203 and 204, back to the source of energy 205 forming the "holding circuit" just referred to. This circuit maintains the current passing through the coil 196 and holds the relay 197 closed. Inasmuch as the passing of an imperfection and the consequent light reduction in the light sensitive cells is only momentary, the flowing of the current in the relay circuit and through the coil 196 is of short duration.

The period during which the relay 183 is held closed and time during which the "preparing circuit" controlled thereby is maintained are only of short duration and this necessitates the establishment of the "holding circuit." It should be pointed out, however, that the recovery of the glow tube 168 is sufficiently slow in its action to insure full establishment of the "holding circuit" and continuance of the energizing of the coil 196 before the relay 183 is restored to open position.

Simultaneously with the establishment of the "preparing circuit," upon the closing of the relay 183, electrical current flows through the closed contact 188, this producing an "auxiliary preparing circuit" since this circuit prepares certain switches for further action. This current flows from the main lead wire 194 along wire 193, through the switch 95, closed at such a time, along wires 192 and 191, through the contact 188, thence through the element 186 and wire 202 into the coil 199, thence by wires 198, 203 and 204, back to the lead wire 205.

As the coil 199 is energized, the relay 201 operates by means of a moving element 214 therein to complete a "restoring circuit" at a contact 215 which is connected by a wire 216 to the wire 192 and at a contact 217 connecting with a wire 218 which is connected to a coil 219 of a relay controlling the contacts 174, 166 and 177. The opposite end of the coil 219 is connected by a wire 221 to the wire 204.

The "restoring circuit" is thus established and electrical energy passes from the wire 194, through wire 193, switch 95, wires 192, 216, contact 215, element 214 of the relay 201, thence through contact 217, wire 218, through the coil 219, wires 221 and 204, back to the lead line 205. This flow of current energizes the coil 219 and moving elements thereof operate to break the three lines 178, 165 and 184 at the contacts 174, 166 and 177 and restore the glow tube 168 to its normal condition. Since the coil 199 is energized for only a short period the breaking of the three contacts is only momentary.

After the relay 183 and the relay 201 have performed their work and have returned to normal open position the relay 197 remains closed, being held by the energized coil 196 in the "holding circuit." This maintains the "indenting circuit" referred to and in this circuit there is a wire 225 connected to the contact 206 and leading to one side of the indenting solenoid 86, the opposite side being connected by a wire 226 to the lead line 205.

The current flowing through the "indenting circuit" passes from the wire 194, through wire 193, switch 95 and wires 192 and 209, through

the element 208, contact 206 and wire 225, into the solenoid 86 and thence by wire 226 back to the lead wire 205. As long as the solenoid 86 is energized, as previously described, the indenting operation is taking place on the strip 21 and this will continue as long as the coil 196 is energized and the contacts 206 and 207 closed.

The first indentation 93 engaging the roller 96 of the switch 95 breaks the current passing through both the "holding circuits" and the "indenting circuit" whereupon the coil 196 releases the relay 197 and deenergizes the solenoid 86 stopping the indenting action.

It will be evident that the time allowed for the indenting operation depends entirely upon the distance between the indenting feed rollers 31 and 32 and the switch roller 86. The waster spot 94, however, may be located at any position on the strip relative to the space outlining the portion which will subsequently be removed in the formation of an article. For example, in the present embodiment of the invention the beam of light 13 detects a waster spot 94 approximately one and one-half article spaces (designated by the dotted line circles in Fig. 2) from the first indentation 93. This means that the first spot 93 may be opposite the center of an article space or may be in front or in back of the center. This position of the indentations relative to adjacent spaces effects the subsequent sorting of the articles after cutting, as will be further explained.

In actual practice, a surface imperfection is a great exception to the general rule and while the present apparatus indents one and a half or more spaces ahead of an imperfection and while a number of articles cut adjacent a waster spot are sorted as bad, throughout the day's run, the total number of articles rejected is in a very small ratio to the total number of articles formed from the strip. All of the articles passing into the waster pile or box 151 can, therefore, be readily inspected by an operator and those articles having perfect surface conditions may be easily recovered.

The electrical circuits utilized for control of the discharge chutes 145 and 146 by means of their operating solenoid 141 will now be considered and reference should again be had to Fig. 10.

Provision is made for holding the waster chute 146 in discharge position (after it has once been placed there by electrical circuits controlled by the indentations) until all of the articles cut adjacent a set of indentations have been removed. This prevents shifting of the chutes for each stroke of the press. The holding device comprises an intermittently moving ratchet mechanism controlled by an electrical solenoid.

This ratchet mechanism is illustrated in detail in Fig. 9 and comprises a horizontal shaft 231 mounted for rotation in a boss 232 formed in one of the side frames 40 of the press. The shaft 231 is held in position by a nut 233 and carries a disc 234 formed of some suitable insulating material. An outer circular contact ring 235 is embedded in the inner face of the disc 234 and a similar incomplete or split inner ring 236 is also embedded in the face of and carried by the disc. The two rings 235 and 236 are bridged as at 237, as indicated in Fig. 10.

Spring pressed contact buttons 238 and 239 are slideably mounted in insulated bushings anchored in the boss 232, the button 238 and ring 236 being an equal distance from the center of the shaft 231 while the button 239 and ring 75

235 are mutually spaced from the shaft center. The button 238 under the influence of its spring is held in contact with the ring 236 except when its split portion passes adjacent at which time the button contacts the insulated disc 234. Button 239 under the action of its spring, is held in contact at all times with the face of the ring 235.

The shaft 231 (Figs. 3, 9 and 10) carries a toothed ratchet wheel 241, the teeth of which are adapted to be engaged by a pawl 242 pivoted at 243 on an arm 244 loosely mounted on the shaft 231. The pivot 243 also forms a connection for a rod 245 pivotally connected at 246 to a sliding core 247 of a solenoid 248 supported by a bracket 249 (Fig. 3) carried by the press frame 40.

A spring 251 (Fig. 10) is interposed between a wall of the solenoid 248 and a collar 252 carried on the core 247 which normally forces the core and rod 245 outwardly into the position illustrated in Figs. 3 and 10. It should be explained that the showing in Fig. 10 of the parts just described is largely diagrammatic, the ratchet wheel 241 and associated parts having been separated from the disc 234 and its contact elements. This separation is made to more clearly differentiate between the parts, but in reality, (as clearly illustrated in Figs. 3 and 9) the disc 234 and the ratchet wheel 241 are both mounted upon the shaft 231 adjacent each other.

The disc 234 of the chute holding elements and associated parts are adapted to remain normally in what may be termed, a neutral position, this being where the space between the ends of the ring 236 (Fig. 10) is engaged by the button 238. If the pad 131 as it is lowered is engaged by an indentation 93, the electrical connection is closed between the parts 132 and 137 of the pad and two "setting circuits" are established.

A wire 261 connects the wire 205 with the button 238 and a wire 262 connects the block 131 of the pad 131 with the wire 261. The element 132 of the pad is connected by a wire 263 to a mechanical switch 264 having a contact 265 connected by a wire 266 with the solenoid 248. The opposite side of the solenoid is connected by a wire 267 to the lead wire 194.

The switch 264 is adapted to be closed only when the slide 127 is in its lowermost position. The mechanism for actuating the switch is shown in detail in Fig. 1 and comprises a cam ring 271 mounted on the shaft 43 and having a projection 272 in one face thereof. The switch 264 is similar in construction to the switch 95 and is provided with an actuating roller 273 which is momentarily engaged by the projection 272 of the cam ring 271, this engagement closing the switch on each rotation of the crankshaft 43.

It will be recalled that the position of a detected surface imperfection locates the first indentation and the first of a series of indentations may be just out of the path of the descending pad 131. In such an event the "setting circuits" will not be established on that stroke of the press but the next indentation on the following stroke will be within the path of travel of the descending pad 131, and the contacts 132 and 137 will be closed (the switch 264 also being closed).

The first of the "setting circuits" established is a "chute setting circuit" since current passing therein energizes the solenoid 141 and moves the lower chute 146 into discharge position in ample time to catch the article cut from the strip at

that stroke. The current for this circuit flows from the wire 205, through wires 261, 262, contacts 137 and 132, through the wire 263, then separating it flows along a wire 275, a wire 276 (connected between the solenoid 141 and the button 239), through the solenoid 141, thence by a wire 277 back to the feed line 194, thus completing the "chute setting circuit."

Simultaneously the second of the "setting circuits" is established, this being a "time setting circuit" since it sets the disc 234 on proper time while energizing the solenoid 248. Current for this circuit passes from the lead wire 205, through wires 261 and 262, through contacts 137 and 132, wire 263, switch 264 and contact 265, wire 266, 15 through the solenoid 248 and wire 267, back to the lead line 194.

The solenoid 248 which is thus energized draws the core 247 thereof inwardly against the resistance of the spring 251, this action shifting the arm 244 on its shaft 231 as well as partly rotating the ratchet wheel 241 which has a tooth engaged by the pawl 242 at such time. Six teeth are provided for the ratchet wheel 241 and this insures a complete rotation of the shaft 231 in six 25 rotations of the crankshaft 43, this corresponding to six cutting operations of the press.

This energizing of the solenoid 248 causes the shaft 231 to move correspondingly through sixty degrees and to rotate the disc at the same time, 30 The rotation of the crankshaft, however, by reason of the cam projection 272 operates the switch 264 and breaks the current in the "time setting circuit" and a deenergizing of the solenoid takes place. This is after each step rotation of the shaft 35 231 and the solenoid spring 251 immediately moves the pawl 242 back into engagement with the next ratchet tooth.

With the first partial rotation of the disc 234, the ring 236 is brought into engagement with 40 the contact button 238 and a "chute holding circuit" is thereupon established, this being for the purpose of preventing shifting of the chutes at each press stroke as previously mentioned. Current flows from the lead line 205, through the wire 45 261, button 238, ring 236, bridge 237, ring 235, thence out by way of the button 239, wire 276, through the solenoid 141 and by way of the wire 277 back to the lead line 194. This "chute holding circuit" will keep the solenoid 141 energized 50 and the chute 146 in place as long as there is an electrical connection between the button 238 and the ring 236.

The solenoid 248 will be intermittently energized with each movement of the press as long 55 as the current flows through the solenoid 141 and as long as the switch 264 is operating, this being independent of the position of the contacts 132 and 137 of the pad 131. The first movement of the solenoid 248 during any one cycle of movements is effected by the "time setting circuit," as previously described and succeeding actions of the solenoid throughout the cycle are then brought about by a circuit which will be termed an "advancing circuit" since it advances the disc 65 intermittently. The "advancing circuit" uses part of the wiring of the "chute holding circuit" current in the former circuit flowing from the lead line 205 through wire 261, button 238, ring 236, bridge 237, ring 235, button 239, wires 276 and 275, switch 264, contact 265, wire 266, through the solenoid 248, thence by wire 267 back to the lead line 194.

This circuit will be established five times for the cycle of movement selected in this present 75

embodiment of the invention. The last movement of the shaft 231 brings the disc 234 into its neutral position where the button 238 is clear of the ring 236, the button then pressing against the insulated face of the disc in the space between the ends of the ring (Fig. 10). This position breaks the "chute holding circuit" deenergizing the solenoid 141 and allowing the chute 145 to move by gravity into discharge position. It also breaks the "advancing circuit" deenergizing the solenoid 248 and stopping rotation of shaft 231 and disc 234.

It will be evident from the foregoing description that five articles are always discharged into the waster box 151 adjacent a surface imperfection 94 as indicated by the indentations 93 and while only one article may contain the imperfection, articles immediately adjacent are handled as imperfect merely as a safety measure to insure the sorting of the perfect articles. It will be evident that any number of articles can be discharged at such a time, depending upon the number of teeth in the ratchet wheel 241.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The method of sorting articles to be cut from strip stock for surface conditions, which comprises passing a strip through detecting devices, indexing the strip adjacent imperfections in the surface thereof as determined by the detecting devices, cutting articles from said strip and causing the segregation of the articles cut adjacent the indentations.

2. The method of sorting articles to be cut from strip stock, which comprises passing a strip through a beam of light and thereby reflecting it from the shiny parts of the strip into a light sensitive mechanism, indenting the strip adjacent non-shiny parts as determined by the light sensitive mechanism, cutting articles from said strip, and causing the separation of articles cut adjacent the indentations from the articles cut from other parts of the strip.

3. The method of sorting articles to be cut from strip stock, which comprises passing a strip having light reflecting parts through a beam of light and catching the reflected light beam in an electrical, light sensitive mechanism, indenting the strip adjacent parts having non-light and lesser light reflecting surfaces by control of the electrical, light sensitive mechanism, cutting articles from said strip, and separating the articles in accordance with light reflecting and non-light reflecting surface conditions of the strip from which they are cut as indicated, during the cutting operation by the indentations.

4. A method of manufacturing articles from continuous or strip tin plate having perfect and imperfect portions which comprises, automatically indexing said sheet material to distinguish between the said perfect and the said imperfect portions and thereafter separating the sheet into portions and automatically removing the defective portions of the sheet material while using the remainder thereof in the ordinary line of manufacture.

5. An apparatus for sorting articles to be cut from strip stock in accordance with the condition of the surface thereof, comprising in combination, feeding devices for advancing the strip along a predetermined path, detecting means for detecting imperfections in the surface of the said strip during its passage along said path, means for indenting said strip adjacent such surface imperfections, cutting members for removing articles from said strip, and means actuated by said indentations for selectively segregating the articles cut from imperfect surface parts of said strip.

6. An apparatus for sorting articles to be cut from strip stock, comprising in combination, means directing a focussed light beam on a surface of the strip, means controlled by the reflection of the light beam for marking and thereby indicating on the strip areas having relatively poor light reflecting surfaces, cutting members for removing portions of the strip for the formation of articles, and means for collecting in one place the cut portions removed from the poor light reflecting parts of the strip and in another place the cut portions removed from the good light reflecting parts as determined by the indicating marks on the strip.

7. An apparatus for sorting articles to be cut from strip stock, comprising in combination, feeding devices for advancing a strip through a beam of light, means operable by variations in the strength of light reflected from the surface of the strip for impressing indentations in the strip adjacent non-reflecting areas thereof, cutting members for removing articles from the strip, a discharge chute for the cut articles, and means actuated by said indentations for selectively positioning said discharge chute to deliver into different places of deposit the articles cut from the strip adjacent its reflecting and its non-reflecting surfaces.

8. An apparatus for sorting articles to be cut from strip stock, comprising in combination, feeding devices for continuously advancing a strip through a beam of light, means operable by variations in the strength of light reflected from the surface of the strip for impressing indentations in the strip adjacent non-reflecting areas thereof, cutting members for removing portions of the strip, feeding devices for intermittently moving the strip into said cutting members, and means actuated by said indentations for selectively segregating the cut portions of the strip containing the non-reflecting areas.

9. An apparatus for indexing strip stock for sorting articles to be cut from the strip, comprising in combination, feeding devices for advancing the strip through the machine, means extending along a line transverse to said motion for responding to light reflected from a surface of said strip, a source of illumination extending parallel to said light responding means, indenting instrumentalities for impressing indentations along one edge of said strip, and electrical means interposed between said light responding means and said instrumentalities for actuating the latter during diminution of said reflected light.

10. An apparatus for indexing strip stock for sorting articles to be cut from the strip, comprising in combination, a photo-sensitive cell, a source of light, feeding devices for causing the strip to pass adjacent said cell and to reflect said light thereon, means responsive to a change in the illumination of the cell for impressing indenta-

- tions in said strip, and means for interrupting the operation of said indenting means.
11. An apparatus for sorting articles to be cut from strip stock, comprising in combination, a photo-sensitive cell, a source of light, feeding devices for causing the strip to pass adjacent said cell and to reflect said light thereon, means responsive to a change in the illumination of the cell for impressing indentations in said strip, cutting members for removing articles from the strip, and means actuated by said indentations for selectively segregating the articles cut from the strip adjacent said indentations.
12. An apparatus for sorting articles to be cut from strip stock, comprising in combination, a photo-sensitive cell, a source of light, feeding devices for causing the strip to pass adjacent said cell and to reflect said light thereon, means responsive to a change in the illumination of the cell for impressing indentations in said strip, cutting members for removing articles one at a time from the strip, a discharge chute, means controlled by said indentations for shifting said chute in one discharge position for separating the articles cut from the strip adjacent said indentations from the other cut articles and means for holding said chute in said shifted position throughout a predetermined number of cutting operations.
13. An apparatus for sorting articles to be cut from strip stock having surface imperfections indicated by indentations, comprising in combination, cutting members for removing portions of the strip for the formation of articles, a discharge chute, and means operable by said indentations for selectively positioning said chute to separate the articles cut from the strip adjacent the indentations from those cut from the other parts of the strip.
14. An apparatus for sorting articles to be cut from strip stock, comprising in combination, primary feeding devices for advancing the strip along a predetermined path, detecting means adjacent said path for detecting imperfections of said strip during its passage along said path, means for indenting said strip adjacent such surface imperfections, secondary feeding devices for further advancing said strip along a second predetermined path, cutting members located adjacent said second path for removing articles from said strip, means actuated by said indentations for selectively segregating the articles cut from imperfect parts of said strip, and actuating means for said primary and said secondary feeding devices for operating the same in synchronism.

WILLIAM PECHY.
